UNITED STATES PATENT OFFICE.

LEONARD F. JACKLIN, OF STREATOR, ILLINOIS, ASSIGNOR TO THE WESTERN GLASS COMPANY, OF STREATOR, ILLINOIS, A CORPORATION OF ILLINOIS.

DESIGN FOR FIGURED GLASS.

Application filed March 12, 1926. Serial No. 16,896. Term of patent 14 years.

To all whom it may concern:

Be it known that I, LEONARD F. JACKLIN, a citizen of the United States, residing in Streator, county of La Salle, and State of Illinois, have invented a new, original, and ornamental Design for Figured Glass, of which the following is a specification, reference being had to the accompanying drawing, forming a part thereof.

Figures 1 and 2 of the drawings are plan and edge views respectively of a portion of a pane of glass showing my new design.

I claim:

The ornamental design for figured glass substantially as shown.

LEONARD F. JACKLIN.
